Primary Examiner — Marianne Pandozzi*Assistant Examiner* — Jae Liang(74) *Attorney, Agent, or Firm* — Jackson IPG PLLC;
Demian K. Jackson(57) **CLAIM**

The ornamental design for a retaining piece for drinking bottle, as shown and described.

DESCRIPTION

FIG. 1 a perspective view of a retaining piece for drinking bottle showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof; and,

FIG. 8 is a cross sectional view taking along line 8-8 of FIG. 6.
